UNITED STATES PATENT OFFICE.

JOSEPH V. PEACOCK, OF AVON, NEW YORK.

SHOE-POLISHER.

SPECIFICATION forming part of Letters Patent No. 737,135, dated August 25, 1903.

Application filed May 1, 1903. Serial No. 155,106. (No model.)

To all whom it may concern:

Be it known that I, JOSEPH V. PEACOCK, a citizen of the United States of America, and a resident of Avon, in the county of Livingston and State of New York, have invented certain new and useful Improvements in Shoe-Polishers, of which the following is a specification.

The present invention relates to that class of shoe-polishers in which a flexible polishing strip or web tensioned upon a rigid holder head or handle is employed to effect the required polishing operation; and the present improvement has for its object to provide a simple, durable, and compact polishing appliance affording an economical and substantial attachment of the polishing web or fabric to its rigid holder-head and an avoidance of rigid ends or corners and the liability to accidental injury therefrom of the shoe or the foot of the wearer, all as will hereinafter more fully appear and be more particularly pointed out in the claims.

In the accompanying drawings, illustrative of the present invention, Figure 1 is a perspective view of a shoe-polisher embodying the present invention and illustrating a construction in which daubers are arranged at the respective ends of the polisher head or holder. Fig. 2 is a side elevation, partly in section, at line xx , Fig. 3, and illustrating a modified construction, in which a single dauber is arranged at one end of the polisher head or holder. Fig. 3 is a transverse section at line $x'x'$, Fig. 2. Similar numerals of reference indicate like parts in the different views.

Referring to the drawings, 1 represents an elongated grasping-handle of wood or other like light and rigid material and which is provided with longitudinal grooves 2 in its sides for more effective engagement by the fingers of the user.

3 is a longitudinal metal member secured by screws or other usual fasteners to the under side of the handle 1.

4 represents end extensions of the longitudinal member 3, which in the present invention have an angular relation to said member 3 and are spread apart at their free ends, as shown.

5 represents holding-jaws formed by flanges or bends in the free ends of the extension 4

and adapted to be set or pinched down upon the ends of the flexible polishing strip or web, hereinafter described, to secure the same in position in a simple and substantial manner.

6 is the usual flexible polishing strip or web, the ends of which are secured, as before described, to the holder-jaws 5, with the main portion of the strip or web extending under light tension from one extension 4 to the other and a distance away from the grasping-handle 1, as shown. In the present improvement the end portions of the polishing-strip that pass around the end extensions 4 are made of 6; a tubular form and provided with an elastic filling 7 to form cushions at such points and prevent injury to the shoe or foot of the wearer in the actual use of the appliance.

8 represents dauber-pads, formed by pieces of cloth secured in place in the holding-jaws 5 at the same time the ends of the polishing-web 6 are secured in place. Such pads project laterally from the jaws, as shown, so as to be convenient for use.

Having thus fully described my said invention, what I claim as new, and desire to secure by Letters Patent, is—

1. In a polishing appliance of the character herein described, the combination of an elongated grasping-handle, a metallic member secured to said handle and provided with angular extensions, a flexible polishing-strip extending between the ends of said extensions, and means for securing the ends of the polishing-strip to said extensions, the same comprising flanges or bends on the ends of said extensions which are adapted to be pinched upon the ends of the polishing-strip, substantially as set forth.

2. In a polishing appliance of the character herein described, the combination of an elongated grasping-handle, a metallic member secured to said handle and provided with angular extensions, a flexible polishing-strip extending between the ends of said extensions and formed with tubular padded ends, and means for securing the ends of the polishing-strip to said extensions which are adapted to be pinched upon the ends of the polishing-strip, substantially as set forth.

3. In a polishing appliance of the character herein described, the combination of an elongated grasping-handle, a metallic member se-

cured to said handle and provided with angular extensions, a flexible polishing-strip extending between the ends of said extensions, dauber-pads, and means for securing 5 the ends of the polishing-strip and the dauber-pads to said extensions, the same comprising flanges or bends on the ends of said extensions which are adapted to be pinched upon

the daubers and the ends of the polishing-strip, substantially as set forth.

Signed at Avon, New York, this 28th day of April, 1903.

JOSEPH V. PEACOCK.
